BY *William J. Graudall*
ATTORNEY.

UNITED STATES PATENT OFFICE.

DONALD E. SMITH, OF SIOUX CITY, IOWA.

DENTAL BRIDGE.

Application filed December 11, 1922. Serial No. 606,222.

To all whom it may concern:

Be it known that I, DONALD E. SMITH, a citizen of the United States, and a resident of Sioux City, in the county of Woodbury 5 and State of Iowa, have invented certain new and useful Improvements in Dental Bridges, of which the following is a specification.

My present invention aims primarily to 10 provide an improvement in the general construction of a so-called dental bridge dummy.

The invention has for a further object the 15 production of an improved dental bridge dummy of the so-called egg-shaped porcelain tipped and faced type.

Furthermore, the invention provides a 20 dental bridge dummy embodying certain novel features of construction which simplifies the technique of the construction.

Still another object of the invention is the 25 production of an improved dental bridge dummy which thoroughly conforms to the anatomical, sanitary, esthetic and mechanical requirements of dental bridge work.

The invention has for another object the 30 production of a dental bridge dummy so constructed as to afford a dependable seat for, and to which the gold mounting is rigidly secured, and presents a labial or buccal and lingual surface conforming to the natural teeth.

The above and other objects and advantages 35 I successfully attain in the embodiments hereinafter described, defined in the appended claim and illustrated in the accompanying drawings which form a part of this specification and in which like characters of reference indicate corresponding 40 parts throughout the several views, of which,—

Fig. 1 is a proximal elevation of a posterior bridge dummy constructed in accordance with the invention.

Fig. 2 is a vertical section of the same.

Fig. 3 is a plan of the porcelain base portion of the dummy.

Fig. 4 is an inner side or lingual elevation of the same.

Fig. 5 is a proximal elevation of the same.

Fig. 6 is a buccal outside elevation of the same.

Fig. 7 is a vertical section of an anterior bridge dummy.

Fig. 8 is a proximal elevation of the porcelain base portion of the same, and

Fig. 9 is a labial or outside elevation thereof.

Referring to the illustrations, the dummy comprises a porcelain base having an egg-shaped lower end part, 10, adapted to seat on the gum or within the natural root socket of the gum and formed with an outer upwardly-extending side portion, 11, providing in the posterior dummy the buccal 65 surface, 12, and in the anterior dummy a labial surface, 13. The top of the root tip portion, 10, of the base is formed with a substantially flat, horizontal surface, 14, and the sides of the upper part of the root tip 70 portion are preferably cut away, as at 15, to provide an exterior shoulder, 16. The top of the reduced portion, 15, is preferably formed with an upwardly-projecting rib, 17; and the inner side of the upwardly-extending portion, 13, is concave, as at 18 (Figs. 3 and 4). In practice the gold mounting, 19, is cast to the desired shape and adapted to seat upon the surface, 14, the rib, 17, and the shoulder, 16, with the lingual surface of 80 the mounting substantially flush with the face of the root tip portion immediately below the shoulder, 16. The mounting, 19, is cast with a depending pin, 20, preferably having its head, 21, embedded in the mounting, 19. The pin, 20, is inserted in an opening, 22, in the porcelain base portion and firmly secured therein by suitable cement.

Although I have illustrated and described the preferred form of the invention, I would 90 not be understood as being limited to such specific construction, for various alterations and variations may be made in the details of construction and arrangements of parts without departing from the spirit and scope 95 of the invention as defined in the following claims, to-wit:

In combination a dental bridge dummy comprising a porcelain base having an egg-shaped root tip portion and an upwardly-extending outer face edge portion, a mounting therefor, the top of the base having a substantially horizontal surface to serve as a seat for the mounting, the upper end of the 100

root tip portion being reduced to provide an external shoulder on which the mounting seats, an upwardly-extending ridge encircling the top edge of the said reduced portion, thereby forming a depressed portion within said ridge, and a pin adapted to be embedded in the mounting, the base having a vertical opening to receive the pin and in

which the pin may be cemented, the mounting having a depression adapted to receive ¹⁰ the ridge, and a downwardly-projecting lip adapted to engage the external shoulder.

In testimony whereof, I have hereunto set my hand this 28th day of November, 1922.

DONALD E. SMITH.
